VENETIAN BLIND CHANNEL GUIDE
FIXTUREJesse E. Cooper, Los Angeles, Calif., assignor to
Western Venetian Blind Co., Los Angeles,
Calif., a corporation of Delaware

Application October 12, 1932. Serial No. 637,456

7 Claims. (Cl. 156—17)

My invention relates to the combination of a channel guide and a swiveling pin on the end of venetian blind slats to guide the slats in their vertical movement in the channel, also to allow 5 tilting of the slats and to accommodate a slight inclination of the slats in regard to the horizontal.

An object and feature of my invention as regards the channel guide is forming this of a hollow structure with a longitudinal slot with two 10 edges forming the opposite sides of the slot and these edges having a rubber covering. This forms a channel guide, and another feature of my invention is providing a certain number of the slats of a venetian blind with swivel pins which 15 operate in the guide slot between the rubber cushioning edge elements. These pins are provided with a beveled type of head, the construction allowing the slats to partly rotate on the axis of the pins, the pins being confined in the guides 20 by the expanded heads, and also the expanded head being of a construction which allows the slats to be inclined to the horizontal considered lengthwise, that is, the one side of a slat to be higher than the other side.

25 My invention is illustrated in the accompanying drawing, in which:

Fig. 1 is an elevation of a window equipped with a blind having my invention.

Fig. 2 is a detail horizontal section on the line 30 2—2 of Fig. 1 in the direction of the arrows.

Fig. 3 is a perspective view of the hollow channel forming the slotted guide.

Referring first to the guide construction, this is indicated generally by the numeral 11 and is 35 formed mainly of metal having a back section 12, opposite edges 13 and 14, and front strips 15 and 16 with a slot 17 between the edges of these strips. Each of the metal strips at the slot is provided with a protective rubber edging 18; these edgings 40 are formed of strips of rubber rectangular in cross section and having a deep and narrow groove 19 to fit over the strips 15 and 16. These rubber edgings have a sufficiently tight grip on the metal of the strip to adhere thereto and leave an adequate space between the edgings. The slats 20 of the blind may be connected for raising and lowering in the ordinary manner, such as by a lifting 45 cord 21 operating through cross slots 22 in each slat, and the slats being guided by webbing strips 23. The slats may also be inclined in the usual manner, this being illustrated by an inclining device 24 operated by the cords 25 which incline the upper bar 26 and, hence, all of the slats in the same direction.

50 55 A number of the slats are provided with swivel

pins 27. Each pin has a beveled head 28. The pin is of such a diameter that it may move freely in the slot between the edging strips, and the head is of such a diameter that it will not pull outwardly through this slot. The pin is secured 60 to a plate 29, which plate is attached by screws 30 to each slat 20.

In the operation of the channel guide fixture in installing the blind in a window, the swivel pins are inserted through the end of the guide. It will 65 be noted on reference to Fig. 1 that these swivel pins are on about every third slat, this being found sufficient. The channel-shaped guides guide the pins in vertical movement of the slats and on account of the rubber edgings there is a quiet or 70 a silent action. This prevents the noise of the slat ends striking against the window frame and also the noise of the pins against the metal guide strip. The circular pins allow the slats to be inclined for darkening the room or allowing the sunlight to pass through, that is, the slats being 75 rotated on the axis of the pins. The heads of the pins prevent the pins from being pulled out of the guides and, hence, maintain the slats in their adjusted position, and also, on account of the bevel on the heads of the pins, the slats may be inclined upwardly at one end at a considerable elevation above the other end and still maintain the slats in position relative to the guides.

80 Another feature of some importance in my invention is that the rubber strips 18 form a sound deadener should the slats swing longitudinally, as the plate 29 will then strike the rubber instead of the metal front strips 15 and 16, and also on account of the pin 27 being comparatively short, the plate will strike the rubber edgings but the head of the pin would strike the back section 12 of the channel. Thus, a venetian blind made with my 85 construction is quiet in operation and when blown by the wind.

90 Various changes may be made in the details of construction without departing from the spirit or scope of the invention as defined by the appended 95 claims.

100 I claim:

1. In a venetian blind construction, a structure 105 having a longitudinal slot at the side of an opening, a slat having a pin extending longitudinally of the slat, the pin extending through said slot and having an enlarged head to prevent removal from the slot in the axial direction of the slat, said slat being adapted to rotate on the axis of a pin, and the head preventing removal of the pin and 110 slot in a longitudinal direction of such slat, the

- edges of the slot having an edging of resilient material, said material engaging said pin.
2. A venetian blind construction having a hollow channel structure adapted for locating in the vertical side of an opening, said channel structure having inturned marginal strips with a vertical slot between the strips, a slat having a pin secured thereto extending in an axial direction through the slot, said pin having an enlarged head, the head preventing removal of the pin through the slot in an axial direction of the slat, the strips at the slat having edgings formed of resilient material, said edgings having a narrow groove fitted on the edge of the strips.
3. A venetian blind construction having a guide channel structure formed of hollow channel-shaped metal with inturned strips, and a vertical slot between said strips, the strips at the slot having an edging member of resilient material, a slat having a pin secured to its end and extending in an axial direction, said pin fitting in the slot between the edging members and having a head of larger diameter than the space between said members whereby the slat and pin may rotate on its axis but prevent it from longitudinal displacement in the direction of the axis of the slat.
4. A venetian blind construction as claimed in claim 3, said resilient edging material being adapted to engage the end of the slat on which the pin is mounted and form a sound deadening device.
5. A venetian blind having a hollow channel structure adapted for locating on the vertical side of an opening, said channel structure having a
- vertical slot, said channel structure and slot being open at the top, a slat having a pin secured thereto at one end, the pin being in axial alignment with the slot and having a circular head of larger diameter than the pin, said head and pin being insertable through the upper open end of the slot, the pin having a clearance on opposite sides of the slot, and the pin having a clearance from the base of the channel structure whereby when the slot is either inclined or tilted said head cannot be withdrawn from the slot.
6. A venetian blind as claimed in claim 5, the channel structure at the slot having edgings of resilient material, said resilient material forming a sound deadening material to engage the pin and to engage the end of the slat should the slat move longitudinally.
7. A venetian blind construction having a guide channel structure formed of hollow channel-shaped metal with inturned strips and a vertical slot between said strips, the strips at the slot having an edging member of resilient material, the slot and channel being open at the top, the slat having a pin secured to its end and extending in an axial direction, said pin having a circular head of larger diameter than the pin, the pin and the head being insertible in the slot and the channel through the top, there being a clearance between the pin and the edging members and the head and said edging members and the base of the channel whereby on longitudinal tilting or rotation of the slat said head cannot be withdrawn from the slot.
